UNITED STATES PATENT OFFICE.

FRANK M. JOSLIN, OF AMSTERDAM, NEW YORK, ASSIGNOR TO INMAN MANUFACTURING COMPANY, INCORPORATED, OF AMSTERDAM, NEW YORK, A CORPORATION OF NEW YORK.

MACHINE FOR SCORING AND DIEING BOX-BLANKS.

1,118,867.

Specification of Letters Patent.

Patented Nov. 24, 1914.

Application filed July 29, 1912. Serial No. 712,127.

To all whom it may concern:

Be it known that I, FRANK M. JOSLIN, a citizen of the United States, residing at Amsterdam, in the county of Montgomery and State of New York, have invented certain new and useful Improvements in Machines for Scoring and Dieing Box-Blanks, of which the following is a specification.

This invention relates to machines for 10 making paper box blanks and more particularly to the scoring and dieing mechanism.

The objects of the invention are to provide a scoring and dieing mechanism which 15 is especially adapted to make box blanks from a heavy continuously moving web without interrupting the movement of the web.

The invention is especially applicable for 20 use in connection with continuous machines for forming a web and printing the same, such as is shown in application No. 712,130 filed the 29th day of July, 1912, by Horace Inman and myself as joint inventors.

25 The novel features of the invention will be apparent from the following description taken in connection with the accompanying drawings, in which,

Figure 1 is a side elevation of the machine; Fig. 2 is a plan of the same; Fig. 3 is a section on the line 3-3 of Fig. 1; Fig. 4 is a bottom plan view of one of the male dies; Fig. 5 is a bottom plan view of another of the male dies; and Fig. 6 is a 35 plan of the box blank.

Referring to the drawings, *a* indicates a web of paper which may be fed into the machine by any suitable feeding mechanism. The frame of the machine, 10, is 40 supported by means of the legs 11 and carries on its lower side the bearing brackets 12 and 13, the brackets 12 supporting a shaft 14 and the brackets 13 supporting a shaft 15. Secured to the frame in any suitable manner, preferably near its ends, are 45 the upright guides 16, these guides being connected together at their tops by a frame 17.

A cross head 18 is arranged longitudinally of the machine at one side thereof and provided with sleeves 19 which engage two of the rods 16 whereby the cross head is arranged to slide in a vertical plane. A cross head 20 is arranged on the opposite

side of the machine and provided with 55 sleeves 21 engaging two of the guides 16.

At the ends of the shafts 14 and 15 are crank disks 22 having crank pins 23. The cross heads 18 and 20 are provided with the 60 wrist pins 24 and 25 respectively, these pins being connected with the pins 23 by the connecting rods 26. The connecting rods 26 are preferably formed in two sections, connected together by means of turnbuckles 27 which have screw-threaded engagement 65 with the sections of the rods in the usual manner and are held in any adjusted position by means of the lock-nuts 28. The shaft 14 is provided with a sprocket wheel 29 and the shaft 15 is provided with a 70 sprocket wheel 30 of the same size as the sprocket wheel 29 and connected with the latter by means of a driving chain 31, whereby the shafts will rotate in unison. From the drawings it will be seen that as 75 the shafts 14 and 15 rotate the cross heads 18 and 20 will be moved up and down on the upright guides 16.

Arranged on the upper side of the frame 10 are longitudinally extending tracks 32 80 on which run the traction wheels 33 of the carriages 34, these carriages supporting the bed plates 35. At the ends of the bed plates 35 are arranged the upright guides 36 which pass through suitable openings in the die 85 plates 37 and serve as guides for the latter. Each of the die plates 37 has arranged at the ends thereof trunnions on which are mounted the rollers 38, these rollers being confined in suitable grooves 39 on the inner 90 face of the cross heads 18 and 20. The bed plates 35 are connected together by means of the straps 40 which extend along the ends of the bed plates and are connected thereto by means of bolts 41, these 95 bolts being movable in slots 42 and thereby permitting the bed plates to be adjusted longitudinally of the machine. Each of the straps 40 is provided with a wrist pin 43 and by the arrangement just described the 100 carriages 34 and the bed plates 35 are so connected that they will move together longitudinally of the machine.

For the purpose of moving the carriages 34 and the bed plates 35 back and forth on the tracks 32 I have provided a shaft 44 which is mounted in bearing brackets 45 secured to the frame 10. The shaft 44 has

arranged on the ends thereof the wheels 46 which carry the crank pins 47, the latter being adjustable radially in suitable slots 48. The shaft 44 may be driven in any suitable 5 manner, as by means of a power chain engaging the sprocket wheel 49. The wrist pins 43 are connected with the cranks pins 47 by means of the connecting rods 50. By this construction it will be seen that the rotation of the wheels 46 will move the carriages 34 back and forth in the desired manner, and the speed of the shaft 44 is preferably arranged so that the velocity of the carriages 34 when the crank pins 47 are 10 moving directly above or below the shaft 44 will be substantially the same as the velocity of the web α .

The die plates 37 carry suitable cutting and scoring dies which coöperate with corresponding dies carried by the bed plates 35 and the downward movement of the die plates 37 is so timed that the dies engage the web at the time that they are moving in the direction of movement of the web and 15 at substantially the same velocity as that of the web. The die plates 37, as will be readily understood, are moved back and forth longitudinally of the machine by means of the upright guides 36, carried by 20 the bed plates 35 and owing to the fact that all of the die plates are connected with the cross heads 18 and 20 it will be seen that they will be caused to engage the web simultaneously, as the cross heads are reciprocated vertically by the connecting rods 25. The dieing and scoring is therefore effected by means of dies which are moving with the web and at the same speed as the web and therefore it is not necessary, as has been 30 heretofore the case with scoring and dieing mechanism, to interrupt the forward movement of the web. This feature is of great practical importance in machines which handle webs of thick material which is un- 35 wound from rolls of immense weight, as it is utterly impracticable to stop and start the rolls by an intermittent forward feed. By adjusting the crank pins 47 in the slots 48 the stroke of the carriages 34 may be 40 regulated and by means of the slots 42 the positions of the dies may be adjusted for the purpose of producing boxes of various shapes and sizes.

The web α moves through the machine in 45 the direction of the arrow and the set of dies at the entrance end of the machine are those which cut the openings α and make the cross score y and also the cut z by which the blank is severed from the web, as clearly 50 shown in Fig. 6. The male die of the set at the entrance end of the machine is shown in Fig. 5. The male dies for making the cuts α' and the cross scores y' are shown in Fig. 4 and are carried by the succeeding 55 carriages 34.

At the delivery end of the machine is arranged a pair of upright brackets 51 which support a pair of feed rollers 52 and 53, these rollers being operatively connected by means of a pair of gears 55, driven by a 70 sprocket wheel 56 and a chain 57 from a sprocket 58 on the shaft 15. The feed rolls 52 and 53 are preferably arranged to have a peripheral velocity exceeding the velocity of the web so that when the blank has been 75 severed from the web these rolls will quickly draw the blank from the machine.

It will be understood by those skilled in the art that various changes may be made in the details of the mechanism within the 80 scope of the claims and therefore I do not wish to be limited to the precise details which I have shown and described.

Having thus described my invention, what I claim is:

1. In a machine of the class described, the combination of means for continuously feeding a web through the machine, scoring and dieing means, means for moving the scoring and dieing means in the direction of movement of the web and at substantially the same velocity as the web, and reciprocating means for automatically moving the scoring and dieing means at right angles to the direction of movement of the web, whereby 95 the web is scored and died without interrupting its movement.

2. In a machine of the class described, the combination of a frame, means for continuously feeding a web through the machine, a plurality of carriages mounted on said frame, means adjustably connecting said carriages together, means for moving said carriages back and forth on said frame in alinement with the web, a plurality of die members movable at right angles to the web, and means connecting said die members and said carriages whereby the die members move back and forth with the carriages.

3. In a machine of the class described, the combination of a frame, means for moving a web through the machine, a plurality of carriages mounted on said frame, means adjustably connecting said carriages together, a shaft having a crank thereon, a connecting rod engaging said crank and adapted to move said carriages back and forth on said frame in alinement with the web when the said shaft is rotated, die members arranged above each of said carriages, means for reciprocating said die members at right angles to said web, and means connecting said die members with said carriages whereby the die members are moved back and forth with the carriages.

4. In a machine of the class described, the combination of a frame, means for feeding a web through the machine, a carriage 130

- mounted on said frame, a shaft having a crank thereon, means connecting said shaft with said carriage whereby the carriage is moved back and forth on said frame in alinement with the web when the said shaft is rotated, a die member arranged above said carriage, members engaging said die member and relative to which the die member is adapted to move longitudinally of the machine, means for reciprocating said members at right angles to said web, and means for connecting the said die member with said carriage whereby the die member is moved back and forth with the carriage. 5
- 15 5. In a machine of the class described, the combination of a frame, means for continuously feeding a web through the machine, a carriage arranged on said frame, a shaft having a crank thereon, means connecting said crank and said carriage whereby the carriage is moved back and forth on said frame in alinement with the web when the shaft is rotated, a die plate arranged above said carriage and adapted 20 to move back and forth with the carriage, means movable transversely of the web for reciprocating said die plate at right angles to the web, and means for adjusting said last-mentioned means whereby the stroke 25 of said die plate may be adjusted relative to the web.
6. In a machine of the class described, the combination of a frame, a carriage mounted on said frame, a shaft, a member arranged on said shaft, a crank pin carried by said member and adjustable thereon radially relative to the shaft, means connecting said carriage and said crank pin whereby the carriage is moved back and 30
- 35 forth on said frame when said shaft is rotated, a die plate arranged above said carriage, and reciprocating means adapted to move said die plate toward and away from said carriage while said carriage is in motion. 40
- 45 7. In a machine of the class described, the combination of a frame, a carriage mounted on said frame, a shaft, means whereby said shaft is adapted to move said carriage back and forth on said frame; a die plate arranged above said carriage and movable with the latter, a cross head engaging said die plate, a pair of shafts provided with cranks, and a pair of rods connecting said cranks and said cross head and adapted to reciprocate the cross head in a direction at right angles to the direction of movement of said carriage. 50
- 55 8. In a machine of the class described, the combination of a frame, a carriage mounted on said frame, a shaft, means whereby said shaft is adapted to move said carriage back and forth on said frame, a die plate arranged above said carriage and movable therewith, a pair of cross heads engaging the ends of said die plate, a pair of shafts having cranks thereon, and pairs of rods operatively connecting said cranks and said cross heads and adapted to reciprocate the cross heads and said die plates 60 at right angles to the direction of movement of said carriage. 65
- 70 In testimony whereof I affix my signature in presence of two witnesses.
